SHOE LASTING DEVICE

Philip Aroney and Walter H. Scott, Chicago, Ill.,
assignors to A. & S. Shoe Engineering Co., Inc.,
Chicago, Ill., a corporation of Illinois

Application April 23, 1934, Serial No. 721,859

22 Claims. (Cl. 12—7)

The invention relates generally to shoe machinery and more particularly to a device for lasting shoes.

In the manufacture of shoes, the upper must be stretched over a last and drawn in around the sole to give the proper shape to the upper. In some types of shoes, this work is done after the welt has been sewed to the upper. One of the common methods of holding the upper tightly against the last is to place a wire around the shoe at the seam between the upper and the welt, and draw it tight against the seam. Since the instep of the shoe, at said seam, is narrower than either the heel or toe portions, the lasting must be done in two operations, one for the toe portion and one for the heel portion, in order that the entire periphery of the upper may be properly shaped. When the wire is drawn around one portion, the ends are inserted through lateral holes in the last at the instep and are twisted together to hold the wire tight against the shoe. After the wire is once used it is scrapped.

The general object of the present invention is to provide a novel lasting device capable of properly lasting the entire shoe in one operation.

It is also an object to provide a lasting device which may be quickly and easily applied and which may be used indefinitely without having to scrap any part thereof, as in the case of the wire in the above-described prior practice.

Another object is to provide a lasting device which causes the upper to be drawn tightly against the last around the entire periphery thereof and which is self-locking so that it remains securely in place until removed.

Still another object resides in the provision of a machine used in connection with the lasting device, which is adapted to facilitate the application of the device to the shoe and which is so constructed that the operator's hands are free to assist in properly drawing the upper around the last while the device is being moved into position.

Other objects and advantages will become apparent from the following description taken in connection with the accompanying drawings, in which:

Figure 1 is a side elevation of a machine and lasting device embodying the features of the invention.

Fig. 2 is a front elevation thereof.

Fig. 3 is an enlarged fragmentary front elevation of the coacting parts of the lasting device and machine.

Fig. 4 is an enlarged fragmentary plan view of the structure shown in Fig. 3.

Fig. 5 is a plan view of the preferred form of lasting device.

Fig. 6 is a vertical section taken on the line 5—6 of Fig. 5.

Fig. 7 is a fragmentary vertical section taken on the line 7—7 of Fig. 5.

Fig. 8 is a plan view of a modified form of lasting device.

Fig. 9 is a vertical section taken on the line 9—9 of Fig. 8.

In Figs. 5 to 9 of the drawings, the shoe is shown in dotted lines and comprises an upper 11 having stitched to the lower edge thereof a welt 10. To provide a form over which the upper may be shaped, a last 13 of the usual type is provided. The shape of the last is that of the interior of the finished shoe, and the sides of the last are therefore rounded inwardly at the sole. The upper, being made of relatively flat pieces of material, must be drawn in at the sole to fit over the rounded portions of the last. The upper must also be maintained in such condition until it is permanently set. In usual practice, the upper, if made of leather, is moistened before such shaping and is allowed to dry in its shaped condition so that the shape will be permanently retained. The sole may also be attached before the leather is dry in order to assist in maintaining the proper shape.

A lasting device embodying the present invention is adapted to draw the upper tightly onto the last to fit the rounded portions thereof, and to maintain the upper in such condition until permanently set. The device is such that the entire periphery of the upper is lasted or shaped in one operation. The device is constructed of parts which fit against the seam joining the welt and the upper, and which contract about said seam to draw the upper inwardly. Broadly, the lasting device comprises a flexible element adapted to be drawn tightly around one end of the shoe, and a member adapted to fit around the other end of the shoe. On the ends of the flexible element are means which are shaped to co-operate with said member in such a manner that, when the flexible element is drawn tightly against the shoe, the end portions thereof are forced against the sides of the shoe, and the parts are locked in place.

In the preferred embodiment shown in Figs. 5, 6 and 7, the flexible element comprises a wire 14 made of spring steel or the like so that it may be drawn into the shape of the shoe with-

out becoming permanently bent. The wire is preferably placed around the toe portion of the shoe and is positioned in the groove formed by the seam joining the upper and the welt, as shown in Fig. 6. The wire is of sufficient length to extend rearwardly to the instep of the shoe, and on each end of the wire, a strip of metal 15 is securely attached, as by welding. The two strips 15 are positioned edgewise toward the shoe and 10 extend rearwardly of the shoe so that the wire may be drawn against the shoe.

For the heel portion of the shoe, a plate 16 is provided which is U-shaped so that its inner edges will fit snugly against the upper. Thus, substantially the entire periphery of the upper may be drawn in around the last.

To enable the parts to be properly positioned relative to the shoe, the plate 16 and the strips 15 are constructed to cooperate with each other 20 to force the wire against the shoe and to lock the parts in place. To this end, the side edges of the plate 16 are reversely bent as at 17 to provide grooves receiving the strips 15 and holding them edgewise relative to the shoe. The plate 25 and strips may thus slide relative to each other as the plate is moved forwardly and the strips are pulled rearwardly to draw the wire tight.

At the instep of the shoe which is considerably narrower than the toe, it is desirable to force the 30 wire laterally inward transversely to the line of tension thereon when the strips are pulled rearwardly. For this purpose, the strips are provided with cam surfaces 18 on their outer edges adjacent their forward ends. These cam surfaces 35 flare outwardly and bear against the folded edges 17 of the plate. Thus, on relative movement between the strips and the plate, the cam surfaces 18 force the forward ends of the strips inwardly and the wire is drawn in at the instep of the 40 shoe. The cam surfaces also have a wedge action against the plate which frictionally locks the parts in place.

To facilitate the application of the device to the shoe, a machine is provided which is preferably foot-operated so that the worker's hands are free to assist in drawing the upper around the last as the device is being tightened. The machine preferably comprises a bench 20 supporting a post 21 provided with an upwardly extending 45 pin 22 upon which the last 13 is detachably mounted with the sole upward and the toe pointing away from the position of the worker.

The machine is constructed to draw the strips 15 on the ends of the wire rearwardly and, when 50 the wire is taut, to force the plate 16 forwardly. To draw the strips rearwardly, a pair of laterally spaced levers 23, pivoted intermediate their ends, are provided. The levers, in order to be readily attached to the strips, have headed pins 60 24 at their upper ends, the pins being inserted in key-hole slots 25 in the rear ends of the strips. To the lower ends of the levers 23 is attached a chain 26 or the like passing over a fixed pulley 27. The other end of the chain is 65 attached to a pedal 28 pivotally supported by a bracket 29 secured to the floor under the bench. When the pedal is depressed the levers 23 pull the strips 15 rearwardly, causing the wire 14 to be drawn tight around the shoe.

To force the plate 16 in place, a slide 30 is 70 mounted in guides 31 on the bench. The outer end of the slide has an upstanding portion 32 extending rearwardly of the shoe and an abutment 33 is mounted thereon which is adapted to 75 abut against the rear edge of the plate 16 to

force it into place. The rear edge of the plate is preferably bent upon itself as at 39, to strengthen it. After the plate 16 is slid onto the strips 15, the abutment 33 is moved vertically from an out-of-the-way position on the upstanding portion 5 32 of the slide to abut against the rear edge of the plate 16. For convenience in moving the abutment 33, it is provided with a handle 34. In moving the plate 16 into place, the grooves formed by the bent over portions 17 are of sufficient width 10 to receive not only the strips 15 but also the heads of the pins 24, so that the plate 16 may be moved into place after the strips are attached to the pins 24.

It is preferable to move the plate 16 into holding engagement with the shoe after the wire has been drawn tight. It is also preferable to employ the same means for doing this as for moving the levers 23. For this reason, a spring 35 is positioned within the guides 31 to resist movement 20 of the slide 30, and the levers 23 are pivotally supported by a pin 36 extending through the upstanding portion 32 of the slide. By this arrangement, pressure on the pedal 28 first causes the levers to tighten the wire, the spring resisting 25 movement of the slide. When the wire becomes tight, further pressure on the pedal moves the slide forwardly against the resistance of the spring 35 and forces the plate 16 into place, the levers 23 swinging sufficiently, as the pivot pin 36 30 shifts, to keep the wire tight. To provide for adjustment of the resistance offered by the spring 35, an adjusting screw 37 is provided. After the plate 16 has been moved into place, the pedal is released and a spring 38 lifts the pedal thereby 35 releasing the levers 23 and slide 30. The shoe, together with the last and the lasting device clamped in place, may then be removed from the machine. Thus, the lasting device may remain fixed on the shoe and be carried with it through 40 subsequent operations, for example, until the sole is laid.

The modified form of lasting device shown in Figs. 8 and 9 is constructed to act upon the shoe in a similar manner to the device shown in Figs. 5, 6 and 7. It, however, differs in the manner in which the strips on the ends of the wire and the plate are moved relative to each other. In this form, the strips, indicated at 50, and the plate, indicated at 51, are provided with laterally registering slots 52. One edge of each slot in the plate 51 is toothed as at 53 and the opposite edges of the slots in the strips are toothed as at 54. To cooperate with these teeth, keys 55, correspondingly toothed, may be inserted in the slots to mesh with the teeth on both the plate and the strips, and on rotation of the keys, the parts of the device are drawn into position. Thus, the device may be tightened manually. If, however, it is desired to use this form of the device on the 60 machine shown in Figs. 1 to 4, the strips 50 are provided with key-hole slots 56 to fit over the pins 24 on the levers 23.

In the operation of lasting a shoe with the device shown in Figs. 5, 6 and 7, the shoe with the last therein is placed on the post 21. The wire 14 is then placed around the toe of the shoe in the groove formed by the seam joining the welt and the upper, and the ends of the strips 15 are drawn rearwardly and attached to the pins 24 on the levers 23. By depressing the pedal 28 part way, the wire is drawn tight around the toe of the shoe. The plate 16 is then slid onto the strips, the grooves formed by the bent over por- 75

tions 17 being wide enough to permit the heads of the pins 24 to pass through the groove. When the plate is pushed forwardly far enough so that the abutment 33 may be moved up into engagement therewith, the pedal 28 is depressed as far as possible. Since the wire 14 already is tight, the further depression of the pedal causes the slide 30 to move forwardly against the resistance of the spring 35, since the slide 30 serves as a support for the levers 23. At the same time, the levers 23 swing still farther to keep the wire tight. As the plate 16 moves forwardly, the cam surfaces 18 on the strips cause the ends of the wire to be drawn inwardly against the instep of the shoe to shape the upper at that point. The cam surfaces 18 also act as a wedge in the grooves formed by the bent-over portions 17 of the plate, when the ends of the wire are forced into the instep. The strips and plate are thereby frictionally locked together to hold the parts in place on the shoe. During such movement of the parts the worker's hands are free to draw the leather of the upper over the last so that it may be clamped in the proper position by the lasting device.

On releasing the pedal 28, the spring 38 draws it upwardly and permits release of the pressure on the levers 23. The shoe, together with the last and the lasting device, may then be removed from the post and the strips detached from the pins 24. When the shoe has been held long enough to permit the upper to retain the shape permanently, the lasting device may be removed from the shoe merely by moving the strips 15 relative to the plate 16. The device is thus ready for use on another shoe.

The lasting device shown in Figs. 8 and 9 may be used on the machines shown in Figs. 1 to 4. It may also be manually clamped on a shoe without the use of the machine by inserting keys in the slots 52 to mesh with the teeth 53 and 54 and rotating the keys. Such rotation shifts the strips 50 longitudinally of the plate 51 until the two are wedged together, thus frictionally locking the parts together.

From the above description, it will be apparent that we have provided a lasting device capable of lasting the entire periphery of a shoe in one operation. The lasting device may be easily applied to the shoe by the machine disclosed herein, and the machine may be operated by the foot so that the operator's hands are free to assist in drawing the leather of the shoe into proper position on the last. When the lasting device is set into position, it is self-locking so that the shoe may be indefinitely held in shape after being removed from the machine. After the device is removed from the shoe, it is ready for use again.

60 We claim as our invention:

1. A lasting device of the character described comprising, in combination, a flexible member adapted to fit around the toe of the shoe, a pair of strips attached to and extending rearwardly from the respective ends of said flexible member and adapted to be drawn rearwardly to tighten the flexible member around the toe, and a heel plate shaped to fit snugly around the heel of the shoe, said strips and said plate having cooperating portions shaped to hold the ends of the flexible member tightly against the shoe and to frictionally hold the strips and plate against relative longitudinal movement.

2. A shoe lasting device comprising, in combination, a flexible member adapted to fit around

the toe of the shoe, a U-shaped member adapted to fit around the heel, and means on the respective ends of said flexible member for drawing the latter tightly around the toe, said U-shaped member and said means being shaped to cooperatively hold the ends of the flexible member tightly against the shoe and to frictionally lock each other in place.

3. A shoe lasting device comprising, in combination, a flexible member adapted to be drawn tightly around one end of the shoe, a rigid member adapted to fit around the other end of the shoe, and means on the ends of said flexible member cooperating with said rigid member to hold said members tightly against the shoe and to lock them in place.

4. A shoe lasting and holding device adapted to be retained on the shoe until the sole is laid comprising, in combination, a flexible member adapted to be longitudinally drawn tight around one end of the shoe, and means for engaging the ends of the flexible member and constructed to lock said flexible member against longitudinal movement and to force said flexible member laterally against the shoe.

5. A shoe lasting device portable with the shoe through subsequent operations comprising, in combination, a flexible member adapted to be drawn tight around one end of the shoe, a pair of strips secured to the respective ends of said flexible member, and means cooperating with said strips to lock them in place and to force the ends of the flexible member against the shoe.

6. A shoe lasting device comprising, in combination, a wire adapted to be drawn around the toe of the shoe, a pair of strips secured to the respective ends of said wire, and a clamp engaging said strips and adapted to cam the strips laterally against the shoe as the strips are drawn rearwardly and to frictionally hold the strips against movement.

7. A shoe lasting device comprising, in combination, a flexible member adapted to be drawn tight around the toe portion of the shoe and extending rearwardly to the instep, a rigid member adapted to fit around the heel portion of the shoe, and end elements secured to the respective ends of said flexible member and fashioned to engage said rigid member and lock the parts in place and to force the ends of the flexible member inwardly at the instep by the engagement with the rigid member.

8. A shoe lasting device comprising, in combination, a wire adapted to be drawn tight around the toe portion of the shoe, a U-shaped member adapted to fit around the heel portion of the shoe, and a pair of strips secured to the respective ends of the wire and adapted to frictionally engage with the U-shaped member to lock the parts together.

9. A shoe lasting device comprising, in combination, a wire adapted to be drawn tight around the toe portion of the shoe, a pair of strips secured to the respective ends of said wire with the inner edges of said strips in alignment with the wire, and a U-shaped member adapted to fit around the heel portion of the shoe and shaped to frictionally engage and hold said strips in place, said strips being shaped to be forced inwardly at the instep of the shoe when in engagement with the U-shaped member.

10. A shoe lasting device comprising, in combination, a wire adapted to be drawn tight around the toe portion of the shoe, a pair of strips ex-

tending rearwardly from the respective ends of said wire and having the inner edges in alignment with the wire, and a plate having a slot shaped to fit around the heel portion of the shoe and having its side edges bent to slidably receive said strips and to frictionally lock therewith when forced into place on the shoe.

11. A shoe lasting device comprising, in combination, a wire adapted to be drawn tight around the toe portion of the shoe and to extend to the instep of the shoe, a pair of strips rigidly secured to the respective ends of the wire with the wire and the inner edges of the strip in line, and a plate having a slot shaped to fit around the heel portion of the shoe, the side edges of plate being bent reversely to form longitudinal grooves receiving the outer edges of said strips, the outer edges of said strips at the forward end thereof being shaped to provide outwardly flaring cam surfaces adapted when engaged with said plate to force the forward ends of said strips inwardly and thereby draw the wire tightly against the instep of the shoe.

12. A shoe lasting device comprising, in combination, a wire adapted to be drawn tight around the toe portion of the shoe and to extend to the instep of the shoe, a pair of strips rigidly secured to the respective ends of the wire with the wire and inner edges of the strips alined, and a U-shaped plate adapted to fit around the heel portion of the shoe and having its outer side edges folded upon itself to provide slots receiving said strips and hold them edgewise against the shoe, said strips extending rearwardly beyond the rear edge of said plate to permit the strips to be drawn rearwardly while the plate is forced forwardly.

13. A shoe lasting device comprising, in combination, a flexible member adapted to be drawn tight around the toe portion of the shoe, a pair of strips secured to the respective ends of said flexible member, a plate shaped to fit around the heel portion of the shoe and to hold the strips flatly against the face of the plate, said plate having longitudinally extending slots registering with corresponding slots in the strips, one edge of each slot in the plate and the opposite edges of the slot in each strip being provided with teeth, and a toothed key fitting in said slots to mesh with the teeth thereof and adapted by rotation to draw the flexible member and the plate tight against the shoe.

14. A machine for lasting shoes comprising, in combination, a work support adapted to support a last to receive the shoe, a flexible member adapted to be drawn tight around the toe portion of the shoe, a pair of strips attached to the respective ends of the flexible member and extending rearwardly of the shoe, a U-shaped plate adapted to fit around the heel portion of the shoe and shaped to force said strips against the sides of said shoe, lever means shaped to engage said strips and to draw them rearwardly, a slideable support for said lever means adapted to engage the rear edge of said plate to force it forwardly, and means for swinging said lever means and for forcing said support forwardly when the lever means have drawn the flexible member tight against the shoe.

15. A machine for lasting shoes comprising, in combination, a work support adapted to support a last to receive the shoe, a flexible member adapted to be drawn tight around the toe portion of the shoe, a pair of strips attached to the re-

spective ends of the flexible member and extending rearwardly of the shoe, a U-shaped plate adapted to fit around the heel portion of the shoe and shaped to force said strips against the sides of said shoe, a pair of levers shaped at their upper ends for engagement with the ends of the respective strips and draw them rearwardly, a slideable element pivotally supporting said levers intermediate their ends and adapted to engage the rear edge of said plate to force it forwardly, a spring resisting forward movement of said element, and a pedal for swinging said levers to draw the flexible member tight against the shoe and then to force the slideable element forwardly.

16. A machine for lasting shoes comprising, in combination, a bench adapted to support a last to receive the shoe, a wire adapted to be drawn tight around the toe of the shoe, a pair of strips attached to the respective ends of the wire to extend rearwardly therefrom along the respective sides of the shoe, said strips being apertured at their rear ends, a U-shaped plate adapted to fit around the heel portion of the shoe, a support slidably mounted on said bench and adapted to engage the rear edge of said plate to force the plate forwardly against the shoe, a spring resisting forward movement of said support, a pair of levers pivoted intermediate their ends on said support and having pins at their upper ends to engage in the apertures in said strips, and a pedal connected to the lower ends of said levers and adapted to exert a forward pull on said lower ends which first draws the wire tight against the toe and then moves the support forwardly to force the plate against the heel.

17. A shoe lasting device portable with the shoe through subsequent operations comprising, in combination, a flexible member adapted to be drawn tight around one end of the shoe, substantially rigid elements engaging said flexible member on opposite sides of the shoe, and means cooperating with said elements and said flexible member to force the latter laterally against the sides of the shoe and to lock the parts in place.

18. A lasting device of the character described comprising, in combination, a flexible member adapted to fit around the toe of the shoe, means attached to said flexible member and adapted to be drawn rearwardly to tighten the flexible member around the toe, and a heel plate constructed to fit snugly around the heel of the shoe, said means and said plate cooperating to hold the flexible member and the heel plate in position on the shoe.

19. A machine for setting a shoe lasting device comprising a flexible member adapted to be drawn tight around one end of the shoe, and means adapted to fit around the other end of the shoe and constructed to cooperate with said flexible member to lock said means and said flexible member in place, said machine comprising, in combination, a work support adapted to fixedly support a last for the shoe, a slideable element adapted to engage said means to force it against the shoe, lever means pivotally supported on said slideable element and adapted to draw said flexible member in a direction opposite to the movement of said slideable element, and means for swinging said lever means to draw said flexible member tight and move said slideable element in the opposite direction to force said means against the shoe.

20. A machine for setting a shoe lasting device comprising a flexible member adapted to be

drawn tight around the toe of the shoe, and a heel plate adapted to fit around the heel of the shoe, said heel plate and said flexible member being adapted to be held firmly in place on the shoe, said machine comprising, in combination, a fixed work support adapted to support a last for the shoe, a slideable element having a portion movable into contact with said heel plate to force it into position on the shoe, lever means engageable with said flexible member and adapted to draw said flexible member tight around the toe of the shoe, and a pedal for swinging said lever means, said lever means being pivotally supported on said slideable element whereby said flexible member is drawn tight and said heel plate is forced against the shoe by a single movement of said pedal.

21. A machine for setting a shoe lasting device comprising a flexible member adapted to be drawn tight around one end of the shoe, and a plate adapted to fit around the other end of the shoe and cooperating with said flexible member to hold each other in place on the shoe, said

machine comprising, in combination, a work support adapted to support a last for the shoe, an element adapted to abut against said plate to force it into position on the shoe by relative movement between said shoe and said element, means for causing said flexible member to be drawn tight around the shoe by a relative movement between the shoe and said means, and a pedal for effecting said relative movements.

22. A lasting device portable with the shoe through subsequent operations comprising, in combination, a flexible member adapted to fit around the toe of a shoe, a U-shaped plate adapted to fit around the heel of the shoe, and means movable longitudinally of the shoe for drawing said flexible member tight around the toe of the shoe and for forcing said U-shaped plate tight against the heel and simultaneously forcing said flexible member laterally against the sides of the shoe.
